(No Model.)

M. A. WIER.

DEVICE FOR FORMING AND DECIPHERING SECRET COMMUNICATIONS.

No. 449,723.

Patented Apr. 7, 1891.

UNITED STATES PATENT OFFICE.

MARSHALL A. WIER, OF LONDON, ENGLAND.

DEVICE FOR FORMING AND DECIPHERING SECRET COMMUNICATIONS.

SPECIFICATION forming part of Letters Patent No. 449,723, dated April 7, 1891.

Application filed September 30, 1890. Serial No. 366,706. (No model.)

To all whom it may concern:

Be it known that I, MARSHALL ARTHUR WIER, engineer, a subject of the Queen of Great Britain, and residing at 3 Palace Grove, 5 Upper Norwood, London, in the county of Surrey and Kingdom of Great Britain, have invented a new or Improved Method of Forming and Deciphering Secret Communications, of which the following is a specification.

10 This invention relates to a new or improved device for forming and deciphering secret communications, which, besides being applicable to the formation and deciphering of cryptographic or code messages in general, for 15 transmission by telegraph or otherwise, is specially applicable for use in connection with the improved apparatus for producing and deciphering secret writing, for which I applied for a patent in the United States on 20 August 22, 1888, Serial No. 283,461. For this purpose I employ what I call a "bi-letter code," which consists of special combinations of couplets of letters (in combination, or not, with what I call "distinguishing letters") to represent the various words or groups 25 of words of the intended message. For example, the letters A A may represent the word "abandon," the letters A B the word "abate," the letters B A "against," and so 30 on, or each pair or couplet of letters may represent a complete sentence or group of words instead of a single word. It will be seen that by the employment of these combinations twenty-six times twenty-six—equal to six 35 hundred and seventy-six words or groups of words—can be represented if the entire alphabet is employed; but as I employ certain letters—say K V W Z, for example—exclusively as distinguishing letters, as will be 40 hereinafter more fully explained, say twenty-two letters only are available for use in the construction of couplets, thus giving twenty-two times twenty-two, or four hundred and eighty-four couplets. As four hundred and 45 eighty-four words or groups of words would be ordinarily insufficient for the purpose of constructing cryptographs or secret communications, I, after having applied words or groups of words to the first four hundred and 50 eighty-four couplets, insert a distinguishing letter—K, for example—between the two let-

ters forming the next set of four hundred and eighty-four couplets A K A, A K B, &c., and apply words or groups of words to these couplets, and so on for each of the four distinguishing letters; and I thus obtain a total of five times four hundred and eighty-four, equal to two thousand four hundred and twenty couplet combinations, representing the same number of words or groups of words, which is generally sufficient for all practical purposes. A cryptograph or secret communication, when written out in these couplets, simply consists of a series of letters, which appear to have been taken indiscriminately, thus F J 55 O P L K S R W E R B A Z T; but if the communication is sent by telegraph it will be received divided into groups of letters, according to the particular rules of the telegraph companies that may be in force at the 60 time with regard to cipher messages. I will assume it to be five letters to a group. In such a case the message will be received in this form: F J O P I L K S R W E R B A Z T. The receiver would divide this message into 65 couplets, taking care to regard either of the letters K, V, W, or Z, wherever it occurs, as forming no part of the couplet, but only as distinguishing the part of the code to which the couplets formed by the letters on either 70 side of such distinguishing letters belong. He would accordingly write out the message in the following way, viz: F J, O P, L^k S, R^w E, R B, A^z T, and he would then find from that part of his code not marked with a distinguishing letter the meaning of the couplets F J, O P, R B, which have no distinguishing letters, and from those parts of his code marked K, W, and Z the meaning of the couplets L S, R E, and A T in those respective 75 parts. The formation or construction of a cryptograph or secret message is effected by the reverse process.

For the purpose of facilitating the formation and deciphering of cryptographic or code 80 messages composed of arbitrary figures or letters, or combinations thereof representing intelligible words, it has heretofore been customary to arrange such arbitrary figures or letters and their corresponding intelligible 85 words in printed or written parallel columns 90 arranged bookwise and to prepare or decipher 95 100

the cryptogram by referring to these columns of ciphers and words. This is a troublesome and tedious operation, which it is one of the objects of the present invention to obviate, 5 while facilitating the use of my above-described bi-letter code. For this purpose I employ the means or apparatus hereinafter described, and illustrated in the drawings hereto annexed, in which Figure 1 is a partial plan 10 of one form of the apparatus; Fig. 2, a section of same on line 1 2 of Fig. 1, and Fig. 3 a partial plan of a slightly-different arrangement of such apparatus.

Referring to Figs. 1 and 2, A is a sheet, 15 board, or tablet having a number of divisions marked on the upper surface thereof, formed by lines drawn at right angles to each other or otherwise. In each of these divisions is written or printed a couplet of letters. A 20 movable sheet, board, or tablet B, corresponding in size to the base-board or tablet A, is adapted to be placed over the latter or to be removed therefrom at pleasure.

The upper surface of the movable board or 25 tablet B is divided into divisions by lines exactly corresponding to those marked on the base-board or tablet A, and the divisions on the movable board or tablet B have written or printed in them the word corresponding to 30 the couplet of letters written or printed on the corresponding division of the base-board.

Guides are provided on the base-board or tablet A, so that when the movable board B is placed over the base-board the divisions on 35 the former will stand exactly over those on the latter, so that any given word on the movable board will stand immediately over its corresponding couplet on the base-board below. In the example shown in the drawings the board 40 or tablet B is arranged to slide over the surface of the board or tablet A, being guided in the grooves C of the lateral guides D.

At one side or end of the base-board is pivoted, as at E, for example, an arm F of sufficient length to sweep over the entire surface 45 of the base-board on which the divisions are marked. On this arm is arranged a sliding pointer G, which can be adjusted into any position longitudinally on the said arm.

50 Assuming now that it is desired to prepare a cryptographic or secret communication, the movable board or tablet B is slid in until the edge B' comes against the stop A', so that the first column of words on the movable board 55 B, commencing with the word "abandon," stands over the first column of couplets on the base-board A, commencing with the couplet A A. The first word of the intended cryptogram is then found on the movable board B, 60 and the arm F is moved round its pivot E until it stands over that word. The pointer G is then slid along the arm F till it also comes over the said word. The movable board is then drawn out from under the arm F and 65 pointer G, leaving them unmoved. When the movable board is drawn out beyond the pointer G—as in the position shown in the drawings,

for example—the pointer G remains standing over the couplet of letters corresponding to the word to which it was set on the movable 70 board B. This couplet is written down by the operator and forms the first element of the desired cryptograph or secret communication. The movable board B is then replaced, the 75 next word of the communication is found thereon, the arm and pointer adjusted over it, the movable board again withdrawn, and the second couplet will be found under the pointer, and so on for each word of the intended 80 communication.

By having several separate boards similar to B, but each having a different series of words written in its divisions, and each having a distinguishing letter, such as K, V, W, or Z, as above mentioned, applied to it, the 85 whole of the two thousand four hundred and twenty words or combinations of words, as above described, can be utilized by placing the distinguishing letter K, V, W, or Z, corresponding to the board used, between the letters of the couplet found on the base-board A. The deciphering of a cryptogram is effected by proceeding in a reverse order. Instead of a pivoted arm, a bar may be arranged to slide parallel to itself over the aforesaid boards, the 90 pointer being arranged to slide longitudinally on such bar.

Fig. 3 of the drawings shows a slightly-different arrangement of the apparatus. A is a transparent sheet of celluloid or other suitable transparent material, on which are printed or otherwise formed in suitably-arranged divisions the four hundred and eighty-four couplets, for example, hereinbefore referred to. This sheet A is capable of being raised 105 up and turned over, like the leaf of a book, along the edge A* A*. Five other sheets or boards, (preferably opaque,) the first of which need have no distinguishing mark, but the other four of which may be marked, respectively, K V W Z, as before explained, are arranged bookwise below the transparent sheet A. Each of these sheets or boards is arranged to turn over, like the leaf of a book, along their edges B* B*, and have written or printed on 115 them words in positions corresponding to the divisions on the transparent sheet A, so that when the latter is laid over one of the opaque sheets the words on the latter appear through the divisions on the former, as shown 120 in the drawings. For example, the word "abactus" on the opaque sheet next below the transparent sheet A is seen in the division containing the couplet A A on the transparent sheet A. In composing a cryptograph 125 or secret communication each required word is first found on one of the five sheets or boards, the sheets that happen to be above it being turned over out of the way on their edges B* B*, the transparent sheet A is placed 130 over the sheet where the said word occurs, and the couplet of letters which appears on the transparent sheet above the said word is written down by the operator, and if the said

word occurs on the sheet marked K, for example, he inserts the distinguishing letter K between the two letters of the couplet, which indicates to the receiver that the corresponding word is to be found on the K sheet under the particular couplet on the transparent sheet A.

The words shown on the movable board in Fig. 1 are intelligible words, and the secret communication may be translated by its aid directly; but it is obvious that instead of intelligible words code-words may be employed, which would require the use of a code-book to effect their translation to or from the couplet ciphers. Similarly the words shown in Fig. 3 are code-words; but they may be intelligible words, if preferred.

I employ distinguishing letters, as above explained, instead of distinguishing numbers, for the reason that combinations of cipher letters and numerals are not at present allowed by the telegraph companies to be used; but if and when numbers are allowed to be used in combination with cipher letters, numerals may be used instead of letters to distinguish the sheets or tables of words with the result that the whole twenty-six letters of the alphabet may be used to form couplets giving twenty-six times twenty-six equal six hundred and seventy-six couplets instead of four hundred and eighty-four, when four of the letters are reserved as distinguishing letters, and as any number of numerals might be used the number of words or ciphers that could be employed is practically unlimited.

It will be understood that the communication consisting of couplets, as above described, after being arranged or set up, may be transposed by the aid of the cryptographic type-writing system described in the specification filed with my before-mentioned application for patent in such a manner as to render it impossible of interpretation except by a person having the key.

It is obvious that in the apparatus shown

in Figs. 1 and 2 the couplets might be written or printed on the movable board B, and the words on the base-board A; but in that case several base-boards would be required to one movable board, which would not be so convenient an arrangement as that shown. It is also obvious that in the apparatus shown in Fig. 3 the words may be written or printed on several transparent sheets, and the couplets on a opaque sheet which can be placed under any one of the transparent sheets.

It will be understood that Figs. 1 and 2 show only one corner of each apparatus, the remainder being obviously of similar arrangement, and that in Fig. 3 each of the sheets is shown broken away to expose a part of the sheet next below it.

I claim—

1. A movable sheet or board containing words to be translated into cryptograms, in combination with a sheet or board containing cryptographic characters, the said sheets or boards being superposed and having each word arranged directly under or over each cryptographic sign or set of signs, substantially as set forth.

2. A movable sheet or board containing words to be translated into cryptograms, in combination with a sheet or board containing cryptographic characters, and a movable pointer arranged and adapted to indicate any one of said words, the said sheets being superposed and each word being arranged directly under or over the corresponding cryptographic character or combination, substantially as set forth.

In testimony that I claim the foregoing as my invention I have signed my name in presence of two subscribing witnesses.

MARSHALL A. WIER.
